UNITED STATES PATENT OFFICE.

HUGO JUNKERS, OF AACHEN, GERMANY.

LIQUID-HEATING APPARATUS.

1,133,563.

Specification of Letters Patent. Patented Mar. 30, 1915.

Original application filed May 21, 1907, Serial No. 374,851. Divided and this application filed December 30, 1913. Serial No. 809,466.

To all whom it may concern:

Be it known that I, HUGO JUNKERS, a subject of the King of Prussia, residing at Aachen, No. 68 Bismarckstrasse, in the 5 Kingdom of Prussia, Empire of Germany, have invented certain new and useful Improvements in Liquid-Heating Apparatus; and I do hereby declare the following to be a full, clear, and exact description of the 10 invention, such as will enable others skilled in the art to which it appertains to make and use the same.

This invention relates to improvements in a liquid-heating apparatus of the character 15 disclosed in United States Letters Patent No. 1,085,341 granted to me January 27th, 1914, of which this application is a division.

The claims of the above-mentioned patent are, for the main part, directed to the 20 feature that the channels of the liquid-containing structure are closer together at the region of the greatest heat-absorption by the mantle, thereby causing a more perfect interchange of heat between the heating gases 25 and the liquid. According to the present invention the interchange of heat is still further increased by the fact that, at the region of the greatest heat-absorption by the mantle, the latter possesses a greater 30 cross-section and hence a greater capacity for absorbing and conducting the heat. This can be effected by reinforcing the mantle at this region by means of sheet-iron plates which are in heat-conducting connection 35 with the mantle. The mantle may also be reinforced by enlarging it at intervals in the direction of the flow of heat, that is to say by causing the mantle to become thicker toward the places where the liquid-containing 40 channels are fastened. Moreover, the necessary increase of the cross-section can be obtained by properly constructing the plates absorbing the heat of the combustion gases.

45 In the accompanying drawings: Figure 1 is a vertical section of the liquid-heating apparatus and Fig. 2 is a horizontal section of the same, the upper part being taken on line A—B and the lower part on line C—D of 50 Fig. 1, while Fig. 3 is a section of the unwound lamel heating body showing a special construction of the lamels.

Above the gas burner 1 is arranged the combustion chamber formed by mantle 2, 55 which carries in heat-conducting connection

therewith the liquid-containing structure of channels, forming preferably a spiral 3. At the upper part, the region of the greatest heat-absorption by the mantle, the channel-spiral is preferably wound more closely than 60 elsewhere. Besides, there is arranged in this region the lamel heating body which consists of plates 5 radially arranged between the mantle 2 and a central inner cylinder or hood 4 which is closed at the top, so that the 65 combustion gases are forced to take their way through this heating body. The plates absorb the heat from the heating gases and transfer it by the medium of the mantle and the liquid-containing channels to the liquid. 70

According to the invention, the heat-conducting cross-section of the mantle is enlarged at the region of the greatest heat-absorption. As is to be seen from Fig. 1, this is accomplished by simply inserting between the mantle 2 and plates 5 a cylinder in such a manner that it will be in a heat-conducting connection with the two parts and so as to cause an enlargement of the mantle. In a channel-structure in which the channels 80 extend vertically on the mantle, this can be effected by constructing the heat-absorbing plates or lamels as shown in Fig. 3, according to which the plates consist of U-shaped bent sheet-iron strips 6, 7 having differently 85 spaced shanks and their stems being fastened one within the other and on the mantle, so that one tube or channel always is arranged or situated at that part of the mantle which is reinforced in the manner described. 90

I claim:

1. In a liquid heater, the combination of a cylindrical wall forming a combustion chamber, a burner at the lower end of the chamber and tubes for a liquid to be heated 95 mounted on the wall of the chamber and arranged closer together over an area distant from the burner than they are over an area closer to the burner the wall of said chamber being increased in thickness over 100 the area where said tubes are arranged closer together to increase the capacity of the wall for absorbing heat and transmitting heat to the liquid in the tubes, substantially as described.

2. Apparatus for facilitating the interchange of heat between a gas and a liquid comprising a metallic mantle, heat-absorbing plates arranged close together in the gas passage within the mantle and near one end 110

thereof and arranged to divide the gas into thin layers, said plates being in full heat-conducting connection with the body of the mantle and said mantle being thickened to 5 increase the heat conducting capacity of the portion thereof surrounding said plates, and a liquid-containing structure of metallic channels in full heat-conducting connection with the mantle and covering a much larger 10 surface area thereof than the area exposed to the gas, substantially as described.

3. In a liquid heater, the combination of a cylindrical wall forming a combustion chamber, a burner in the lower end of the 15 chamber, a substantially cylindrical hood closed at its upper end mounted within the

upper end of the chamber, the wall of said chamber being thickened over the portion thereof surrounding said hood, a plurality of plates arranged radially between the hood 20 and chamber, and liquid-containing tubes affixed to the wall of the chamber about said hood and below the same, substantially as described.

In testimony whereof I have signed my 25 name to this specification in the presence of two subscribing witnesses.

HUGO JUNKERS.
